(57) **CLAIM**

The ornamental design for a color-coded power center having peripheral-specific indicia, as shown and described.

DESCRIPTION

A portion of the disclosure of the this design patent application document contains material to which a claim for copyright is also made. The copyright owner has no objection to the facsimile reproduction of this design patent application by anyone as it appears in the Patent and Trademark Office patent file or records, but reserves all other copyrights whatsoever.

FIG. 1 is a perspective view of the color-coded power center having peripheral-specific indicia, in accordance with the present invention.

FIG. 2 is a plan view of the color-coded power center having peripheral-specific indicia, in accordance with the present invention, as depicted in FIG. 1.

FIG. 3 is a frontal view of the color-coded power center having peripheral-specific indicia, in accordance with the present invention, as depicted in FIG. 1.

FIG. 4 is a side view of the color-coded power center having peripheral-specific indicia, in accordance with the present invention, as depicted in FIG. 1.

FIG. 5 is an underside of the color-coded power center having peripheral-specific indicia, in accordance with the present invention, as depicted in FIG. 1.

FIG. 6 is a rear view of the color-coded power center having peripheral-specific indicia, in accordance with the present invention, as depicted in FIG. 1; and,

FIG. 7 is a corresponding side view of the color-coded power center having peripheral-specific indicia, in accordance with the present invention, as depicted in FIG. 1.
